Attorney

UNITED STATES PATENT OFFICE.

HENRY P. DAVIS, OF NEW YORK, N. Y.

AUTO-WINDOW FRAME.

1,389,033.

Specification of Letters Patent. Patented Aug. 30, 1921.

Application filed August 3, 1918, Serial No. 248,119. Renewed October 25, 1919. Serial No. 333,376.

To all whom it may concern:

Be it known that I, HENRY P. DAVIS, a subject of the King of Great Britain, residing at New York, in the county of New York and State of New York, have invented new and useful Improvements in Auto-Window Frames, of which the following is a specification.

This invention relates to window frames and particularly to frames for use in connection with automobiles, vehicles or the like wherein leather or similar material constitutes a part of the super-structure of the vehicle in which the window opening is formed. The invention is in the nature of an improvement upon my co-pending application filed March 15th, 1918, Serial No. 222,706, and my co-pending application filed March 23, 1918, Serial No. 224,109.

20 The essential object of the present invention is to provide complementary frame sections which are adapted to be connected together or disconnected efficaciously and which will include mating parts for positively utilizing the cloth with which the frame sections are associated as a weather proof sealing means between the complementary sections of the frame.

Another object of the invention is to provide complementary sections, one of which is provided with a radially yieldable clamping means co-acting with the other section to hold both sections operatively closed against each other, and a continuous cloth crimping means operating relatively of both sections to fold the cloth in a sinuous manner entirely around the outside joint between both sections.

In the drawings:

40 Figure 1 is a front view of the frame in applied position.

Fig. 2 is a section therethrough taken on line 2-2 of Fig. 1.

Fig. 3 is an inner face view of one of the 45 sections.

Fig. 4 is a similar view of the other section.

Fig. 5 is a transverse section through one section of the frame.

50 Fig. 6 is a similar view through the other section of the frame.

Fig. 7 is an edge view of a portion of one of the sections.

I do not wish to limit myself to any particular details of construction but desire to lay particular stress upon the provision of

complementary sections of a frame wherein will be provided, means for crimping the cloth which constitutes a part of the vehicle top and for positively sealing the outside joint between the respective sections of the frame to establish a perfect water tight connection.

In practice, use is made of complementary sections 10 and 11, which may be constructed of any suitable well known material, such as nickel silver, celluloid or any suitable well known material. The section 10 in the present instance is of an oval formation but obviously can be made in various shapes and designs and at one side it is provided with a panel receiving flange 12 against which the marginal edge of a suitable transparent panel 13 is seated, a suitable waterproof cement 14 being arranged between the marginal edge of the panel and the flange 12 to seal the joint and establish a perfect water tight connection. The flange is upset angularly at 15 to entirely surround the marginal edge of the panel and if desired, use may be made of panel engaging clips 16 which are secured within said section 10 and provided with bendable ends 17 adapted to engage against the inner face of the panel as clearly illustrated in Figs. 2, 3 and 5. After the panel is cemented in position, the ends 17 of the clips are upset against the panel and the tendency thereof is to advance the panel against the cement 14 and thus establish a uniform application of the marginal edge of the panel against the cement. At the opposite side the section 10 is provided with an inwardly extending flange 18 which lies approximately in the same general plane with the flange 12, the same being spaced therefrom so that the channel 19 within the section 10 will have clearance entirely around the section for a purpose to be hereinafter explained.

The section 11 is of course identical in shape with the mating section 10 and at one side it is provided with a wall 20 having a flange 21 which is arranged in parallel relation to the flange 18 of the section 10 so that the two constitute a clamp between which the cloth 22 is received. From the flange 21 the section 11 is curved at 23 and then inwardly at 24 to provide crimping means which will operate to fold the edge of the cloth as at 25. This retaining means is continued into lateral resilient spring fingers 26 which are terminally

curved at 27 in order that they may be freely guided into the channel 19 of the section 10 and co-act with the flange 18 and thereby yieldingly hold the crimping means 5 against the cloth and bind the latter against the inner edge 28 of the mentioned flange 18. In folding the cloth in a sinuous manner as just described and providing a non-interrupted or continuous clamping means 10 to engage therewith at the immediate joint between both sections of the frame, an extremely effective water proof connection is established.

Should the panel 13 become broken, the 15 two sections of the frame can be readily separated by simply inserting a suitable tool therebetween and springing said sections apart. This is desirable in order that a new panel may be substituted for a broken one 20 at the convenience of the user and without requiring the skill of a mechanic. The spring fingers 26 extend entirely around the

frame section 11 in order that their full contacting and clamping value can be utilized and the frame section held against any 25 casual separation incident to vibrations or shocks and jars that might be transmitted thereto.

What is claimed as new is:—

In a device of the class described, the combination of a frame section having inwardly extending flanges at each edge, a plurality of clips having bendable ends adapted to co-act with one of said flanges to secure a panel thereto, and a second frame section 30 having a flange at one edge only and adapted to co-act with one of the flanges of the first said frame sections for securing the device to a curtain, and having a plurality of 35 spring fingers extending completely around 40 its flange for securing the sections together.

In testimony whereof I affix my signature.

HENRY P. DAVIS.
